UNITED STATES PATENT OFFICE.

LOUIS J. HOMAN, JR., OF CINCINNATI, OHIO.

TRACING TOOL.

Application filed January 17, 1925. Serial No. 3,186.

This invention relates to a hand tool particularly adaptable for tracing around an object, as a foot, for obtaining or drawing an outline pattern thereof.

5 An object of the invention is to provide a hand tool formed at one end with a pair of jaws, or holders for removably securing a stylus or lead tracing point in relation to a guiding edge of the tool which engages the object. The guiding edge is sustained by the body of the tool when slid over the surface of the sheet to engage the object in approximately perpendicular or definite angular relation to the surface or sheet upon 10 which the tracing or pattern of the object is made, the guiding edge also in cross section being concentric with the axis of the stylus or tracing point so that the tool body can be followed in any angular position 15 with relation to the outline edge of the object without impairment to accuracy of the tracing or pattern outline.

Another object is to provide a device which can be cheaply constructed preferably 20 of strip sheet material.

At present the invention finds its most important and useful application in obtaining accurate outline drawings of the human foot, these drawings being used as patterns 25 for determining the appropriate last and shoe size to fit the shape and dimension of the foot represented by the pattern, primarily for mail order service.

It is customary for the purchaser of shoes 30 ordered through the mail to draw an outline of his feet upon a sheet of paper using an ordinary pencil for tracing around the foot. The layman usually does not possess sufficient skill or take the necessary precaution required in making an outline pattern with a pencil to obtain the same with a fair degree 35 of accuracy which could be relied upon for figuring the size and last of shoes that will give him a proper and satisfactory fit. Consequently considerable returns are made resulting in added expense as for transportation charges, shoe refinishing cost, and damage to the shoes and loss in transmission due 40 to the purchaser's failure to properly repack the goods.

It is also difficult to trace the outline of a foot with a pencil, because of the difficulty for one to always keep the pencil in a properly guided position without any definite 45 guiding aid.

With the use of the tool of the present

invention the tracing of a pattern outline can be easily and accurately executed, by merely placing the foot upon a sheet of paper disposed upon a flat surface, allowing 60 the tool to rest upon the paper with the guiding edge thereof bearing against the foot and sliding the tool in such position around the foot. As the guiding edge is curved in cross section concentric with the 65 axis of the stylus or marking point, no definite lateral positioning of the tool is necessary, the only requirement being that the tool rests upon the flat surface with the 70 guiding edge bearing against the foot.

Other objects and certain advantages will be more fully set forth in the description of the accompanying drawing forming a part of this specification, in which:

Figure 1 is a plan view of the device 75 shown in operative relation in tracing the outline of a foot.

Figure 2 is a side view, the tracing end of the implement broken away to show the lead.

Figure 3 is a cross section on line 3—3 of Fig. 2, showing the construction and arrangement of the clamping means.

The device is preferably constructed as shown and is herein formed from a resilient 85 strip of sheet or strip material of rectangular configuration which is bent upon itself to provide a broadened handle or body portion substantially of isosceles triangular configuration, one side 1 of the handle serving to sustain the tool in an upright position when placed upon a table. Extending from one apex of this triangular handle are two arms 3, 4, as prolongations of the two sides. The arms are substantially parallel and lie 90 substantially at right angles to the terminal side 1 of the handle, thus providing a symmetrically shaped device as an open frame, either edge side of which is adapted to lie 95 flatly against a flat surface to be marked.

The arms 3, 4, are adapted to be brought flatly together with their edges flush to form a clamping jaw for the tracing element, such as a pencil lead. The right angularly disposed extremities 5 or edges, of the arms are 100 rounded and act, when the arms are brought together in clamping position, as a working or guiding edge engageable with the perimeter of the object, of which an outline is to be traced. The guiding edge is curved or 105 rounded to a degree so as to be concentric with the axis of the stylus or marking point.

The tool therefore can be brought to any angle with the perimeter of the object without changing the distance the marking point bears to the guiding edge, and which offers more latitude to the user in sliding the tool about the object with the guiding edge always bearing against the object.

On the inner faces of each arm is a groove 6, in this instance placed in a direction at 10 right angles to the long axis of the arm and parallel with the edge 5. The grooves are opposingly related and are registerable when the arms are brought together to clamp the stylus or lead. The grooves are preferably 15 spaced inwardly from the terminal work engaging edge whereby an outline slightly larger than the object can be obtained, which is desirable when taking the outline of a foot.

The arms or jaws are forced together by 20 means of a headed screw 8 and thumb nut 9 located midway the length of the arm, the screw passing loosely through one arm. When the nut is unscrewed the arms separate by spring action and may thus be adjusted 25 for receiving leads or marking devices of different diameter or shape.

The edge of the straight terminal side 1 of the triangular handle acts to prevent tipping of the implement during use, and 30 thus an outline of the object placed substantially perpendicularly to the surface to be traced upon, may be accurately obtained.

An open frame structure is thus provided, the edge of either open side of which is 35 adapted to lie flatly against the surface to be traced, during the outlining operation.

The device is, therefore, reversible and the opposite parallel edges 10 of the terminal side 1 are adapted to engage the surface and prevent tilting whichever edge is engageable with the surface.

The implement as herein constructed is particularly adapted for use in obtaining the outlines of vertically disposed objects, the tracer being rested upon the surface upon which the outline is to be traced, with the tracing element in substantially vertical position and with one of the sides of the triangular handle element engaged against the surface to positively prevent rocking motion of the implement and thus hold the same in upright position without effort on the part of the operator.

Having described my invention, I claim:

A marking implement comprising a flat 55 strip of resilient material bent upon itself to provide a handle portion having an edge for engagement with the surface to be marked, and two spring retractable opposingly related arms as prolongations of the handle portion, the inner face of each arm having a groove therein at right angles to the long axis of the arm, said grooves registerable when the spring arms are brought together, a pencil element clamped in said 60 registerable grooves and projecting beyond the arms at one side, and means for drawing the arms to and holding the same in clamping position.

In witness whereof, I hereunto subscribe 70 my name.

LOUIS J. HOMAN, JR.
